UNITED STATES PATENT OFFICE.

BARTOLOMEW MCINTIRE, OF SAN FRANCISCO, CALIFORNIA.

RECIPROCATING MECHANISM.

1,306,351.

Specification of Letters Patent. Patented June 10, 1919.

Application filed May 29, 1918. Serial No. 238,792.

To all whom it may concern:

Be it known that I, BARTOLOMEW MCINTIRE, a citizen of the United States, residing in the city and county of San Francisco and State of California, have invented a new and useful Improvement in Reciprocating Mechanism, of which the following is a specification.

My invention relates to improvements in longitudinal and lateral reciprocating mechanism and is especially adapted to operate in conjunction with that type of excavating machines set forth in my application for Letters Patent of the United States, filed on the 19th day of January, 1918, Serial No. 213,798, reference to which is hereby made; and the objects of the present invention are:

First, to provide an improved longitudinal and lateral reciprocating mechanism to operate in conjunction with the excavating machine referred to;

Second, to provide an improved mechanism of the character described adapted to provide an intermittent forward movement and a reciprocating lateral movement;

Third, to provide an improved device of the character described wherein the frequency degree of the forward intermittent movement may be altered and regulated.

I accomplish these several features by means of the improved device disclosed in the drawings forming a part of the present specification wherein like characters of reference are used to designate similar parts throughout the said specification and drawings, and in which—

Figure 1 is a longitudinal sectional view of my improved reciprocating mechanism;

Fig. 2 is a broken plan view with the reciprocating frames removed to disclose the reciprocating mechanism beneath;

Fig. 3 is a transverse sectional view taken on line 3—3 of Fig. 1 in the direction indicated;

Fig. 4 is an enlarged detailed view, partly in section of the connecting rod for the forward intermittent movement;

Fig. 5 is a transverse sectional view taken on line 5—5 of Fig. 3 in the direction indicated;

Fig. 6 is a broken detailed view, on an enlarged scale of the ratchet movement and releasing mechanism therefor; and

Fig. 7 is an end elevation of Fig. 6.

So far as possible, in the following speci-

fication, the same parts of the excavating machine hereinbefore referred to, in so far as they appear in the drawings, bear the same reference numerals as in the said referred to specification in order that said parts may be better located and understood.

Referring to the drawings the numeral 6 is used to designate a power shaft driven from any suitable source of energy not shown. The shaft 6 terminates in a bevel pinion 16 engaging a bevel gear 17 on a shaft 18 provided at its other end with a pinion gear 19 which in turn drives a gear 22 on a shaft 23 provided at each end with pinions 24 which drive a gear 26 on the main shaft 27 which carries the supporting or tractor wheels 28.

The shaft 6 is also provided with a worm 9 which may be connected or disconnected from the said shaft 6 by means of a suitable clutch 11. The worm 9 operates a worm gear 12 to operate a variable speed transmission composed of a shaft 31, rigidly connected to the worm gear 12, and having gears 32, 33 and 34 which separately mesh with and drive gears 36, 37 and 38 respectively on a counter-shaft 39. These gears may be shifted, by means of any suitable shifting device, not shown, to provide various gear ratios between the gears mentioned whereby various speeds may be imparted to the shaft 39 without altering the speed of the shaft 31.

One end of the shaft 39 is provided with a gear 38 which drives a gear 40 located directly above it and connected to a bevel gear 41 in turn meshing with a bevel gear 42 on the end of a longitudinally disposed crank shaft 109 rotatably mounted within a suitable main frame 1.

The shaft 39 of the variable speed transmission unit or group has rigidly connected thereto a pair of diametrically opposed cams 42 arranged to engage a roller 43 and thereby longitudinally reciprocate a sleeve 44 upon the end of which said roller 43 is mounted. The sleeve 44 has slidably mounted therein one end of a rod 45 provided with a slot 46 to engage a lateral key 47 secured to the sleeve 44.

The rod 45 is provided with a collar 48 and a spring 49 is interposed between the said collar 48 and the end of the sleeve 44 to move said rod 45 out of the sleeve, such movement being limited by the key 47 which engages the slot 46, so that said rod 45 may

be moved into the sleeve 44 against the tension of the spring 49, the purpose of which will hereinafter be more fully described.

The free or outer end of the rod 45 is pivotally connected between a pair of cheek plates 50 rotatably mounted on each side of a ratchet 51 secured to the shaft 23. A pawl 52 is mounted between the cheek plates 50 to engage the ratchet 51 and is provided with an extension 53 which is engaged by an arm 54 on a lever 55 to disengage said pawl 52 from the ratchet 51 in a manner hereinafter more fully described.

In operation, when the shaft 39 is rotated through the medium of the variable speed mechanism the diametrically opposed cams engage the roller 43 and longitudinally reciprocate the sleeve 44 and the rod 45 connected thereto thereby causing the pawl 52 to engage the ratchet 51 and intermittently rotate the shaft 23 and propel the frame 1 forward through the shaft 23, pinions 24 thereon and wheel 28.

The sleeve 44 is slidably held in alignment with the cams 42 by means of parallel guide plates 59 depending from and formed integral with a cross bar 56 secured to the under side of the main frame 1.

The frequency of the forward movements is adjusted by means of the variable speed mechanism hereinbefore described. The range or degree of said forward movement may be regulated and adjusted by means of a link 57 from which the sleeve 44 is suspended, the upper end of said link 57 being in turn suspended from a threaded rod 73 rotatably mounted in a nut 74 in turn rotatably mounted in a sleeve 75 secured to the upper end of a vertically disposed standard 76 secured to the main frame 1, the upper end of the nut 74 is provided with a suitable hand wheel 77. By rotating the hand wheel 77 the nut 74 raises or lowers the threaded rod 73 to raise or lower the sleeve 44 to bring the roller 43 thereon into juxtaposition with the center of the shaft 39 and the cams 42 thereon, thereby increasing or decreasing the period of contact and consequently the amount of movement of said cams 42 with the roller 43 and sleeve 44.

By means of this arrangement the degree of longitudinal movement of the sleeve 44 and rod 45 and consequently the arc of rotation of the ratchet 51 may be regulated and adjusted. In order to return the rod 45 and sleeve 44 after each movement the cheek plates 50 are provided with a counter weight 78 as disclosed in Figs. 1 and 2 of the drawings.

It is obvious from the foregoing that as the cams 42 rotate the sleeve 44 and rod 45 will be moved longitudinally. Should the forward movement of the entire machine meet with any undue resistance the movement of the cam 42 operating on the sleeve

44 will compress the spring 49 thereby relieving the mechanism of any strain which might tend to fracture it. The tension of the said spring 49 may be regulated by the nuts 81 as disclosed in Fig. 4 of the drawings. This spring 49 also operates as a shock absorber, thereby greatly reducing vibration and shock which might otherwise tend to damage the mechanism.

In order to disconnect the power shaft 6 from a continuous forward driving movement, a pinion 19 is secured to the shaft 18 by means of a suitable clutch 20 so that while the machine is being moved forward intermittently by means of the pawl and ratchet 51 and 52 the pinion 19 may be disengaged from the shaft 18 by means of said clutch 20.

A superframe 62 is mounted to reciprocate laterally on the main frame 1 by means of upper and lower braces 63 and 64 respectively on the front end of the superframe 62 and the main frame 1 between which braces are mounted rollers 66. The rear end of the frame is slidably mounted on a square shaft 67 secured to the main frame 1.

Upon the superframe 62 a frame 58 is pivotally mounted as at 61 and provided with toothed sectors 72 which are engaged by worms 71. By rotating the worms 71 the position of the frame 58 is altered relatively to the frame 62.

This superframe 62 is reciprocated laterally by means of the crank shaft 109 which is longitudinally disposed and rotatably mounted within the main frame 1. To each crank of the crank shaft 109 are secured connecting rods 110 which are pivotally connected to vertically disposed links 111 whose lower ends are pivotally mounted upon struts or braces 56 secured to the main frame 1.

The upper ends of the link 111 are pivotally connected to the superframe 62.

The operation is as follows:

The shaft 39 is rotated at the desired speed through the medium of the variable speed mechanism hereinbefore described and the gear 38 on the end of said shaft 39 driving the gear 40 and bevel pinions 41 and 42 rotate the crank shaft 109 in turn operating the connecting rods 110 thereby oscillating the link 111 to reciprocate the superframe 62. It is obvious that by altering the speed of the shaft 39 through the medium of the various gear ratios of the transmission mechanism that the frequency of the lateral reciprocations may be adjusted and regulated.

During the forward intermittent movement by means of the pawl and ratchet 51 and 52 should it be desired for any purpose to temporarily arrest said forward movement the same may be accomplished by operating the release 114, pivotally mounted on the link 57 having a connecting rod 115 op-

eratively connective to the lever 55 whose extension 54 will then engage the extension 53 of the pawl 52 and disengage the same from the ratchet 51. When it is desired to 5 resume the forward movement same may be accomplished by releasing the member 114 which will in turn release the pawl 52 so that the longitudinal reciprocations of the rod 45 will operate said ratchet 51.

10 It is obvious from the foregoing that I have provided an improved mechanism whereby a superframe may be laterally reciprocated as well as improved means for regulating the frequency of said movement. 15 Also improved means for moving entire mechanism forward intermittently as well as means for altering and regulating the frequency as well as the range or degree of said forward movement.

20 Having thus described my invention what I claim as new and desire to secure by Letters Patent is—

1. A device of the character described comprising a main frame; traction wheels 25 supporting the main frame; a superframe slidably mounted to move laterally upon the main frame; a longitudinal crank shaft rotatably mounted in the main frame; connecting rods operatively connecting the 30 crank shaft to the superframe whereby said frame may be reciprocated laterally; means for rotating the crank shaft at various speeds to regulate the frequency of the reciprocations; and means for operating the traction 35 wheels intermittently.

2. A device of the character described comprising a main frame; traction wheels supporting the main frame; a superframe slidably mounted to move laterally upon the 40 main frame; a longitudinal crank shaft rotatably mounted in the main frame; connecting rods operatively connecting the crank shaft to the superframe whereby said frame may be reciprocated laterally; means for rotating the crank shaft at various speeds to 45 regulate the frequency of the reciprocations; and means for operating the traction wheels intermittently; and means for regulating the

range and frequency of the intermittent movement of the traction wheels. 50

3. A device of the character described comprising a main frame; traction wheels supporting the main frame; a super-frame slidably mounted to move laterally upon the main frame; a longitudinal crank shaft rotatably mounted in the main frame; connecting rods operatively connecting the crank shaft to the superframe whereby said frame may be reciprocated laterally; means for rotating the crank shaft at various speeds to 60 regulate the frequency of the reciprocations; and means for operating the traction wheels intermittently; and means for regulating the range and frequency of the intermittent movement of the traction wheels; and means 65 for temporarily releasing the traction wheel operating means.

4. A device of the character described comprising a main frame; traction wheels mounted to support the main frame; a super-frame slidably mounted to reciprocate laterally upon the main frame; a crank shaft rotatably mounted within the main frame; connecting rods operatively connected to the crank shaft and to the superframe whereby 70 said frame may be reciprocated laterally when the shaft is rotated; a counter shaft rotatably mounted within the main frame; and operatively connected to the traction wheels; a ratchet wheel mounted upon the 75 counter shaft; a pawl mounted upon said shaft to engage the ratchet; a pair of cams rotatably mounted within the main frame; a rod operatively connected to the pawl and arranged to be reciprocated longitudinally 80 by the cams; and a variable speed transmission unit operatively connected to the crank shaft and to the cams whereby lateral reciprocations may be imparted with varying frequency to the superframe and intermittent 85 movements may be imparted to the main frame by means of the cams, pawl and ratchet.

In witness whereof I hereunto set my signature.

BARTOLOMEW McINTIRE.
